UNITED STATES PATENT OFFICE

FRANK X. LOEFFLER, OF OKLAHOMA CITY, OKLAHOMA

PORTABLE STEAM CONDENSING APPARATUS

Application filed July 3, 1930. Serial No. 465,542.

My invention relates to apparatus for condensing steam, and more particularly to a portable apparatus primarily intended for use in connection with oil field boilers.

The objects of my invention are to provide a device of this class which is new, novel, practical and of utility; which will have a large cooling capacity; which will require a small amount of ground space; which may be moved from one location to another at a comparatively small cost; which will provide an automatic means for supplying to the boiler feed line a minimum amount of water in addition to the water produced by condensation of steam; which will condense steam with a minimum amount of evaporation; which will be strong and durable; which will be less expensive to manufacture and install than the usual cooling towers which are now generally used; and which will be efficient in accomplishing all the purposes for which it is intended.

In a great many localities the supply of boiler water has become quite an item, and consequently it is imperative that the available water supply be conserved as much as is possible. This is particularly true in respect to oil field boilers. Cooling towers are in general use in a great many of the oil fields for condensing and cooling the water from the exhaust steam, but these towers are usually expensive and require considerable ground space which is often not available. The usual tower also is not subject to removal without completely tearing it to pieces. Due to the fact that drilling of an oil well requires only a limited amount of time, and due to the fact that the usual cooling tower is not subject to removal to another site, the cost of these towers in a great many instances has proven prohibitive. The usual cooling tower exposes the water to considerable evaporation.

In the apparatus herein described and claimed, applicant provides a means for condensing the exhaust steam without exposing the steam or water to the evaporative effect of the air. He provides an apparatus which is comparatively easy to move from one location to another. He also provides an automatic means for supplying to the boiler feed

line a minimum amount of water over the amount of water which is produced by the condensation of the steam.

With these and other objects in view as will more fully appear, my invention consists in the construction, novel features, and combination of parts hereinafter more fully described, pointed out in the claims hereto appended, and illustrated in the accompanying two-sheet drawings, of which:

Figure 1 is a perspective view of the complete apparatus showing in dotted lines a float mechanism within the reservoir;

Fig. 2 is a detailed sectional view of the steam outlet in the top of the reservoir; and,

Fig. 3 is an elevational view partially in section of one of the cooling units.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawings are to be interpreted as being illustrative and not restrictive.

One practical embodiment of the invention as illustrated in the drawings comprises,

A portable and removable cooling tower 1 and a portable and removable reservoir 2, the cooling tower comprising supporting members 3 which may be set in concrete or otherwise rigidly positioned. Said supporting members 3 are rigidly fastened together by channel iron members 4 slightly above their mid-portion and channel iron members 4 are fastened together by a plurality of spaced transverse strap members 5. A plurality of cooling units 6 are disposed upon said strap members 5 and are held rigidly thereon by a pair of channel irons 8 at the upper ends of said supporting members 3.

Each of said units 6 comprises a frame consisting of an upper plate 7, a lower plate 8, and sheet metal ends 9. Said upper plate 7 forms the top for a steam box or compartment 11 which is made integral with said

plate 7 and which has both ends closed. A similar box or compartment 12 is provided upon said bottom plate 8 and likewise has its ends closed. Extending between said compartments 11 and 12 and communicating therewith is provided a plurality of hollow tubes 13, each of which is exteriorly provided with a plurality of fins 14 for increasing the exterior surface which may be contacted by the air. Each of said tops 7 are provided with an opening 15 and thereabove with a flanged exteriorly threaded connection or boss 16. Likewise each of said bottom plates 8 are provided with an opening 17 and with a flanged boss 18.

The reservoir 2 comprises a tank having a closed top 19 which is centrally provided with an outlet 20 the details of which may best be seen in Fig. 2 and which will be more fully described later herein. Said reservoir is also provided with an inlet opening 21 and with an outlet opening 22. Said outlet opening is located somewhat near said inlet opening 21 and is connected in the usual manner to the pipe 23 leading to the usual boiler feed pumps, not shown.

Each of the connections 18 in the bottom plate 8 of the cooling units 6 is threadedly connected to a downstanding outlet pipe 24 and all of said outlet pipes 24 are connected to a pipe 25 which communicates with the mid-portion of said reservoir 2. The top of each of said units 6 is connected to an inlet pipe 26 and all of said inlet pipes 26 are connected together by a pipe 27. The steam from the exhaust of the pumps or engines, not shown, is first carried through an oil separator, not shown, for separating any oil which may be carried thereby by the steam, and is thence carried through a pipe 28 to a horizontal pipe 29 which leads beneath said tower which there communicates with said reservoir 2. An upright pipe 30 connects said pipe 27 and said pipe 29 at a point adjacent the inlet end of said tower 1, and acts as a means for conveying the steam to the upper compartment 11 of the cooling unit 6. Said pipe 29 slopes slightly downwardly toward said reservoir 2 from the point where it connects said pipe 30 and at a point adjacent its connection with pipe 30 is provided with a usual manually operated gate valve 31. The inlet opening 21 in said reservoir 2 is connected to a horizontal pipe 32 which is provided with a gate valve 33 and at its outer end is connected to a vertical pipe 34. Said pipe 34 upon its lower end is connected through a T 35 to a water supply line 36. Said supply line 36 extends from said T 35 beneath said cooling tower 1 and communicates through an upright pipe 37 and through an injector 51 with said pipe 29. Said injector 51 is located adjacent the point where said pipe 29 connects said pipe 30. Said line 36 is provided with a cut-off valve 38, and said pipe

34 is also provided with a cut-off valve 39. A drain pipe 40 having a cut-off valve 41 is provided in the bottom of said reservoir 2 for the purpose of draining the reservoir when desired and the reservoir is also provided with a manhole opening 42 which offers a means for permitting the reservoir to be cleaned when desired. At a point slightly above said inlet opening 21 in said reservoir 2 and extending from the outside to the interior of said reservoir 2 is journaled a crank 43 which bears upon its inner end a float 44. The outer end of said crank 43 is pivotally connected to an upstanding arm 45, the vertical movement of which acts as a means for opening or closing said valve 33 in said line 32.

As may best be seen in Fig. 2 the steam outlet in the top 19 of said reservoir 2 consists of a threaded nipple 46 and a conical baffle 47 is connected by strap iron brackets 49 to a nut 50 which is threaded upon the interior end of said nipple 46.

A description of the operation of the device above described follows:

After the apparatus has been installed and the proper connections made upon lines 23 and 36 respectively to the boiler feed pumps and the source of water supply, and line 28 has been properly connected to the oil separator, valve 38 will be closed and valve 39 opened. This will cause the water to flow into said reservoir 2 until it raises said float 44 and actuates said crank 43 to close said valve 33. The boiler feed pumps will then be started and water will flow through said outlet opening 22 and said pipe 23 and the boilers will be filled and fired. As the steam is produced by the boilers for use through pumps or other apparatus, the exhaust steam will pass into said line 28 through said line 29, pipe 30, and pipe 27, and will enter the cooling units 6 through said inlets 26. As the steam thus enters said upper compartment 11 in said units 6 and will consequently enter the tubes 13, and the action of the air upon the exterior of the tubes and upon the fins 14 will condense the steam to water which will flow outwardly from the lower compartment 12 through openings 17 and outlet pipes 24 to pipe lines 25 and thence into said reservoir 2. There will be, of course, some of the steam which has not completely been condensed into water and this steam will form in the upper portion of said reservoir 2. The conical valve 47 necessitates that the steam pass through the space between the upper end of the baffle and the lower surface of the top 19 of reservoir 2 before it may escape through said nipple 46. Any water which is formed by the condensation of the steam passing over the upper edge of said baffle 47 and thence out of said nipple 46 will escape by gravity through the perforation 48 in the lower point of the baffle 47. As long as the level of the water

in said reservoir 2 holds the float at the upper end of its throw, the valve 33 will be held closed but as soon as the boiler uses more water than is being condensed by the cooling tower and the float is permitted to lower itself 5 from the upper end of its throw, said valve 33 will be opened and water will enter the reservoir 2 from the supply line 36. This arrangement insures an ample supply of water 10 at all times for the boiler, but at the same time causes only a minimum amount of water to be fed from the supply line 36 into the reservoir 2. The steam which enters pipe 29 from said pipe 28 will naturally have some 15 condensation and said valve 31 will be slightly opened in order to permit the water thus accumulated in pipe 29 to flow by gravity from pipe 29 to within reservoir 2. As soon as the water which is condensed by the cooling tower 20 1 commences to flow into said reservoir 2, said valve 38 upon line 36 will be slightly opened and a small amount of water will be permitted to enter said pipe 37. The water thus entering said pipe 29 will of course be cool and will consequently assist by mixing 25 with the steam in causing more condensation within said pipe 29. This water will be permitted to flow back to the reservoir through said valve 31 as previously described.

Obviously, the invention is susceptible of embodiment in forms other than that which is illustrated in the accompanying drawings and described herein, and applicable for uses and purposes other than as detailed, and I 30 therefore consider as my own all such modifications and adaptations and other uses of the form of the device herein described as fairly fall within the scope of my invention.

Having thus described my invention, what 35 is claimed and desired to be secured by Letters Patent, is:

1. Apparatus for the purposes described, embodying a cooling tower comprised of removable cooling units for interiorly receiving steam, removable means for rigidly supporting said units, a closed reservoir having a steam outlet in its top, said reservoir connected by pipes to all of said units, and means for automatically controlling the amount of 45 supply water entering said reservoir in accordance with the amount of water condensed by said units and the amount of water used out of said reservoir.

2. Apparatus for the purposes described, 50 embodying a cooling tower comprised of removable cooling units for interiorly receiving steam, removable means for rigidly supporting said units, a closed reservoir having a steam outlet in its top, said reservoir connected by pipes to all of said units, means within said reservoir for obstructing the escape of steam through said outlet, and means for automatically controlling the amount of supply water entering said reservoir 55 in accordance with the amount of water

condensed by said units and the amount of water used out of said reservoir.

3. Organization as described in claim 1, in which each of said cooling units comprises a plurality of exteriorly exposed tubes connected between an inlet compartment and an outlet compartment, said tubes having exterior fins thereon. 70

4. Organization as described in claim 1, and means for supplying cool water to the steam before it enters said units, and means for returning said water together with condensed water to said reservoir without its entering said units. 75

5. Organization as described in claim 2, in which said obstructing means comprises an inverted hollow cone having a perforation in its point, said cone disposed with its base slightly below and around said outlet. 80
